UNITED STATES PATENT OFFICE.

HOY RUNION, OF SPRINGFIELD, MISSOURI, ASSIGNOR TO RICHARDSON BALL BEARING SKATE COMPANY, OF CHICAGO, ILLINOIS, A CORPORATION OF ILLINOIS.

DESIGN FOR A FOOT-PLATE FOR ROLLER-SKATES.

43,063.

Specification for Design.

Patented Sept. 24, 1912.

Application filed June 10, 1912. Serial No. 702,895. Term of patent 7 years.

To all whom it may concern:

Be it known that I, Hoy Runion, a citizen of the United States, residing at Springfield, in the county of Green and State of Missouri, have invented a new, original, and ornamental Design for Foot-Plates for Roller-Skates, of which the following is a full, clear, and exact description, reference being had to the accompanying drawings, forming a part hereof.

My design relates to a foot-plate for roller-skates, and has for its object to provide a device of this character that is neat and artistic in appearance and graceful and rakish in outline.

In the drawings: Figure 1 is a longitudinal side elevation of my ornamental design for foot-plates for roller-skates. Fig. 2 is a bottom plan view of the same.

Referring to the drawings, it will be seen that my design consists of a single plate the front portion of which near the toe is bent in an upward direction and the rear or heel portion is provided with an upturned segmental flange that embraces the shoe-heel of the wearer. The plate conforms in a conventional outline to the sole of the wearer's shoe being reduced in width between its

rounded ends to form an instep, and extending parallel to the side edges of this plate a shallow head is stamped out of the metal.

On the underside of the plate is a forward and a rear truck-plate each having studs projecting therefrom in opposite directions, as shown. These plates are connected by a member having a double compound curve the center of length of which curves downward and contacts with a straight member which latter extends horizontally from the lower end of one stud to the other and connects the same. This completes the structure and adds symmetry and gracefulness to the design, presents a more esthetic appearance thereto, and gives to the skate a speedy and rakish outline.

I claim:

The ornamental design for a foot-plate for roller-skates, as shown and described.

In witness whereof I have hereunto set my hand and set my seal this 28th day of May, 1912.

HOY RUNION. [L. S.]
